UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

DESIGN FOR A CUTLERY-HANDLE.

SPECIFICATION forming part of Design No. 22,503, dated June 6, 1893.

Application filed May 9, 1893. Serial No. 473,610. Term of patent 7 years.

To all whom it may concern:

Be it known that I, CHARLES F. SMITH, a citizen of the United States, residing at New Britain, in the county of Hartford and State of Connecticut, have invented and produced a new and original Design for Cutlery-Handles, of which the following is a specification, reference being had to the accompanying drawings, forming part thereof, in which—

Figure 1 is a side elevation of a cutlery handle showing my design. Fig. 2 is a plan view of the same.

A designates the body of the handle, B the ornamental tip at the butt end, and C the ferrule or ferrule portion of the handle, all of the general contour shown. The ornamental tip at the butt is provided with two narrow bands 3 and 4, while the remaining portion of the

tip is ornamented by combined scroll and leaf ornaments as shown. The ferrule portion 20 C is provided with plain bands 5, 6, 7, 8 and 9. The ornamental band 10 is ornamented with slightly curved transverse ornaments as shown, while the larger ornamental portion 11 is provided with scroll and leaf ornaments, the figure upon each side having the scroll ornaments near one edge of the handle, as at 12 and a branch of leaflets near the other edge of the handle, as at 13.

What I claim is—

The design for a cutlery handle, substantially as herein shown and described.

CHARLES F. SMITH.
